UNITED STATES PATENT OFFICE.

MARTIN L. BERGMAN AND MARTIN L. MILLER, OF BUENA VISTA, OREGON.

SPRING-SHACKLE.

SPECIFICATION forming part of Letters Patent No. 357,169, dated February 8, 1887.

Application filed July 20, 1886. Serial No. 208,561. (No model.)

To all whom it may concern:

Be it known that we, MARTIN L. BERGMAN and MARTIN L. MILLER, citizens of the United States, residing at Buena Vista, in the county 5 of Polk, State of Oregon, have invented certain new and useful Improvements in Spring-Shackles, of which the following is a specification, reference being had therein to the accompanying drawings.

10 This invention relates to shackles mainly for uniting carriage-springs to the body, or other parts of the carriage; and the objects of our improvement are to facilitate the casting and construction of the shackle and adapt it 15 to vibrate forward and backward and also sidewise and in other directions, while all the rattling of the parts is prevented. We accomplish these objects by the construction illustrated in the accompanying drawings, in 20 which—

Figure 1 represents in perspective a wagon-body and one of its axles and springs with shackles constructed in accordance with our invention. Fig. 2 represents, on a larger scale, 25 the same shackles suspended from segmental wagon-springs. Fig. 3 represents in perspective a portion of the same spring and shackle with a coiled spring surrounding the joints of the latter. Fig. 4 is a side view of the shackle 30 and a portion of one of the supports of the wagon-body.

In said drawings, A represents a wagon-body, and A' its metallic supports, secured preferably to the under side thereof.

35 B represents one of the axles, to which are secured, by clips b, springs C, preferably formed of superposed leaves bent in the form of segments, the longest leaf having one end coiled to receive through the loop thus formed a bolt, 40 c, that passes also through the upper ends of links d, while the lower ends of said links receive a bolt, c', that passes through a rectangular block, E. This block is provided with trunnions e, that are received in perforations 45 made in the two upper jaws, f, of a link, F. This link has at its lower end two similar jaws, f', to receive a rectangular block, E', provided also with trunnions e', that enter the perforations in the lower jaws, f', and through 50 the perforation in the block E' is passed the lower end of the wagon-supports A', a nut,

a', on the end of the latter completing their connection with the shackle, composed of the links F and blocks E and E'. To facilitate the connection of these blocks with the links 55 F, the latter consist of two parts secured together face to face in the middle of their length by a rivet, f'', and each has said middle portion, between the single jaw at each end, twisted a quarter of a turn, so that while the 60 axis of the trunnions of the upper block, E, is parallel with the long axis of the body of the vehicle the axis of the trunnions of the lower block, E', is at a right angle to said long axis of the vehicle. This shackle can be made of any 65 suitable size for baby-carriages, buggies, wagons, street and railroad cars.

To keep the parts of the shackle extended, and thus prevent jolting and rattling of its parts, a coiled spring, G, is made to encircle 70 these parts, its upper end being secured to the transverse bolts c, while the opposite end rests either upon the lower jaws or upon the wagon-body supports A' and their nuts a', and prevents the loosening of said nut. A coiled 75 spring, g, may also be used, as shown in Fig. 1, between the wagon-body and its axle, for nearly the same purpose.

Having now fully described our invention, 80 we claim—

1. In combination with the supports of a wagon-body, its spring and links d, a shackle consisting of two links, F, secured together face to face to form jaws at each end, having perforations, with perforated blocks having 85 trunnions to enter the perforations in the jaws of the links, substantially as described.

2. The combination of a wagon-spring and its shackle, consisting of two links secured together in the middle of the length to form jaws 90 at each end, with perforated blocks between said jaws, and a coiled spring surrounding the shackle, substantially as and for the purpose described.

In testimony whereof we affix our signatures 95 in presence of two witnesses.

MARTIN L. BERGMAN.
MARTIN L. MILLER.
